TABLET DISPENSER

Earl J. Hoagland, Chicago, Ill., assignor to Standard Safety Equipment Co., a corporation of Illinois

Application August 23, 1950, Serial No. 11,889

Term of patent 14 years

(Cl. D52—2)

To all whom it may concern:

Be it known that I, Earl J. Hoagland, a citizen of the United States, residing at Chicago, county of Cook, and State of Illinois, have invented a new, original, and ornamental Design for a Tablet Dispenser, of which the following is a specification, reference being had to the accompanying drawing, forming a part thereof, in which:

Figure 1 is a side elevational view of a tablet dispenser, showing the improved design; Fig. 2, a front elevational view; Fig. 3, a bottom plan view; and Fig. 4, a top plan view.

I claim:
The ornamental design for a tablet dispenser, as shown.

EARL J. HOAGLAND.
